UNITED STATES PATENT OFFICE.

THOMAS H. KANE, OF YOUNGSTOWN, OHIO, ASSIGNOR TO TRUSCON STEEL COMPANY,
OF YOUNGSTOWN, OHIO, A CORPORATION OF MICHIGAN.

BUILDING CONSTRUCTION.

Application filed May 15, 1920. Serial No. 381,544.

To all whom it may concern:

Be it known that I, THOMAS H. KANE, a citizen of the United States, and residing at Youngstown, in the county of Mahoning 5 and State of Ohio, have invented a new and Improved Building Construction, of which the following is a specification.

This invention relates to a knock-down metal building construction of the type 10 shown in my prior patent, dated December 12, 1916, No. 1,208,568 and the object of the present invention is to secure main supporting members or columns which will grip the edges of the sheet metal panels in such a 15 manner as to insure a rigid and permanently reliable connection between them thus not only providing a more solid structure but also admitting of the use of thinner sheet metal for the panels.

20 This invention consists in a combination of metal columns and panels adapted for the construction of knock down buildings in which the columns are made of a plurality of parts, which, when secured together, will 25 grip the edges of the sheet metal panels between them, thus avoiding all necessity of depending upon limited areas of the sheet metal panels to take the stresses to which the structures may be subjected by winds 30 and loads.

35 This invention is also embodied in columns for knock down buildings formed of three parts of which the middle part is substantially a flanged bar such as a T-bar or I-beam, while the other two members are angle bars, the several members being connected together by means of slotted bolts and wedges, and when so connected, grip between them the edges of the adjacent sheet metal panels.

40 The invention further consists in the details of construction illustrated in the accompanying drawings and particularly pointed out in the claims.

45 In the drawings, Fig. 1 is a perspective view illustrating the upper end of a column when taken apart to admit the edges of the adjacent panels. Fig. 2 is an elevation of a portion of a column showing the connecting bolt and Fig. 3 is a transverse section of this 50 column. Fig. 4 is an elevation of a portion of a modified form of column and Fig. 5 is a transverse section thereof.

Similar reference characters refer to like parts throughout the several views.

55 In the structure shown in my prior pat-

ent mentioned above, the edges of the sheet metal panels are secured against the sides of the columns by means of slotted bolts and wedges. The invention there set forth has been embodied in hundreds of buildings 60 with great success, but when these buildings are built eighty feet wide and more than three hundred feet long, the stresses on the sheet metal of the panels, because of winds and roof loads, at the limited areas 65 engaged by the bolts and wedges, become quite heavy. The present invention is designed to take these stresses from these limited areas and spread them along the entire edges of the sheet metal panels so that sheet 70 metal of less thickness will be required to withstand the stresses.

As this is the sole invention presented by this application, I have omitted all showing of roof trusses and the manner of connecting them to the columns, and all showings of base plates, these being matters which can be easily designed by skilled engineers after considering the descriptions and drawings of these details set forth in my prior patent 75 aforesaid.

Referring now to Figs. 1, 2 and 3, the column is shown made up of a central T-bar having a head 1, a web 2 and a foot 3. Two angle bars, each having a wide flange 80 4 and a narrow flange 5 may be united to the central member by slotted bolts having heads 6 and slotted shanks 7 which are adapted to pass through proper holes 8 and 9 in the flanges 4 and webs 2. A wedge 10 90 for each bolt is adapted to draw the parts together.

It will be noted that the outer edge 12 of the flange 4 of each angle bar is bent. As a result, when the in-turned edges 13 95 of the sheet metal panels 14 are inserted between the angle bars and the central T-bar, as indicated in Fig. 3, and the wedges 10 are driven in, the intermediate portions of the flanges 4 of the angle bars will be 100 drawn toward each other, which tends to flatten them. As these outer edges engage with the foot 3 of the T bar, the effect is that the flanges 5 are pressed with great force against the portions 13 and 14 of 105 the sheet metal panels. As the engagement between these parts of the columns and the edges of the panels is for the entire height of these members, the union is much stronger than can be possible with any number of 110

fasteners which merely press limited areas of the inturned flanges of the panels against the columns. As a result, the thicknesses of the panels may be very materially reduced.

- 5 In Figs. 4 and 5, the construction is very similar to that just described, excepting that the central member of the column is an I-beam and thus much stiffer than the T bar shown in Fig. 1. The angle bars have 10 the same flanges 4 and 5, and the inturned edges 13 of the panel 14 are gripped between these angle bars and the web 15 of the I-beam while the main portions 14 of the panels are pressed against the flanges 16. 15 The opposite flanges 17 are engaged by the inturned edges 12 of the angle bars.

The details and proportions of this lock between a sheet metal panel and a column made up of a plurality of parts may all be 20 changed by those skilled in the art without departing from the spirit of my invention as set forth in the following claims. It will be understood that when only one panel is to be connected to the column, one of the 25 angle bars may be omitted.

I claim:—

1. A metal building construction comprising a column and two alined sheet metal panels, the vertical edges of the panels being 30 bent inwardly to constitute parallel flanges, the column consisting of a central T bar against whose web and flanges the flanges and main portions of the panels are fitted, said column further consisting of a pair 35 of angle bars and bolts to press the edges of the panel against the webs of said T bar.

2. A metal building construction comprising a column and two alined sheet metal panels, the vertical edges of the panels being 40 bent inwardly to constitute parallel flanges, the column consisting of a central T bar against whose web and flanges the flanges and main portions of the panels are fitted,

said column further consisting of a pair of angle bars and means to press the edges 45 of the panel against said T bar, said T bar being provided with flanges at the edge of its web to furnish footing for said angle bars.

3. A metal building construction comprising a main member embodying a web and two flanges at an angle thereto, two other members consisting of webs and flanges adjacent the web and flanges of the main member, sheet metal panels having their edges 50 bent to fit between said members, and means to force the webs and flanges of said members together to grip said panels.

4. A metal building construction comprising in combination a column consisting of 60 a main member embodying a web and a flange at right angles thereto, and a second member consisting of a web and a flange at right angles to each other, a sheet metal panel having its edge bent at right angles 65 so as to fit between the two column members, slotted bolts extending through alined holes in the column members, and wedges extending through the slots in the bolts and adapted to force them together. 70

5. A metal construction comprising a column and two alined sheet metal panels having inturned upright edges at right angles to the plane of the panels, said column consisting of a central T bar against whose web and flanges the flanges and main portion of 75 the panels are fitted, and of two angle bars of unequal flanges and means to press the wide flanges of the angle bars toward the web of the T bar, the outer edges of the wide flanges being bent toward each other, said T bar being provided with flanges at the adjacent edge of its web to furnish footing for said bent edges of the angle bars. 80

THOMAS H. KANE.
